UNITED STATES PATENT OFFICE.

HOWARD EARL SIMMONS, OF MARION, INDIANA.

TIE FOR PIE AND SIMILAR PLATES.

1,188,209.

Specification of Letters Patent. Patented June 20, 1916.

Application filed May 7, 1915. Serial No. 26,526.

To all whom it may concern:

Be it known that I, HOWARD E. SIMMONS, a citizen of the United States, and a resident of Marion, in the county of Grant 5 and State of Indiana, have invented a new and Improved Tie for Pie and Similar Plates, of which the following is a full, clear, and exact description.

My invention has for its object to provide an economical tie for pie, cake, ice-cream, butter, egg-tray, picnic, social, demonstrating and similar plates and pans.

The tie consists of gummed strips which are disposed transversely around a group of 15 plates, the tie strips being affixed to the end plates and to a wrapper which is disposed around the edges of the plates. The edges of this wrapper are gathered at the edges of the end plates and are held in position 20 by the strips which are affixed thereto to provide rounded and cushioned corners which will prevent the edges of the plates from cutting the strips.

Additional objects of the invention will 25 appear in the following specification in which the preferred form of my invention is disclosed.

In the drawings similar reference characters refer to similar parts in all the views 30 in which—

Figure 1 is a plan view showing a group of pie plates provided with my tie, the ends of one of the tie strips being free from each other to illustrate the construction; Fig. 35 2 is a transverse sectional view of a group of plates held together by my improved tie; and Fig. 3 is a view showing how the wrapper is wound around the edges of the group of plates.

40 By referring to the drawings it will be seen that the pie plates are disposed one over the other to form a group A, and a wrapper B is wound around the edges of the said group of pie plates A, this wrapper extending beyond the end pie plates C and D and being 45 rolled, coiled or otherwise gathered at the edges of the said end plates C and D, this all being clearly illustrated in Fig. 2 of the drawings.

50 The wrapper B is held in position around the edges of the group of pie plates A and the pie plates forming the group A are held together by having the wrapper edges rolled or gathered at the edges of the said end

plates C and D. The parts of the wrapper 55 B may also be glued together to hold the wrapper snugly around the group of plates A. I also prefer to use strips G, these tie strips G being preferably two in number and being disposed transversely around the 60 wrapper B and the group of pie plates A. The tie strips G are gummed so that they are affixed to the wrapper B, to the rolled or gathered edges E of the wrapper and to the end pie plates C and D, the rolled or 65 gathered edges E of the wrapper B forming rounded and cushioned corners to prevent the edges of the end pie plates C and D from cutting the tie strips G. The tie strips G are preferably disposed around the 70 group of pie plates so that they will cross each other at right angles at the end pie plates C and D. The ends of the tie strips G are affixed together.

When plates are bound together in the 75 manner stated they are not damaged, as is the case when rope or twine is used. Rope or twine disfigures crimps and mars the first five or six plates at each end of the package and it also has a tendency to spoil 80 the shape of all of the plates in the package.

Having thus described my invention, I claim as new and desire to secure by Letters Patent:

1. In combination with a group of plates, a wrapper disposed around the edges of the plates and extending therebeyond, and being gathered at the edges of the end plates of the group of plates, and a gummed strip 90 or strips disposed transversely around the group of plates and affixed to the wrapper and to the end plates in the group.

2. In combination with a group of plates, a wrapper disposed around the edges of the 95 plates and extending therebeyond, the wrapper being gathered at the edges of the end plates of the group of plates to form cushions, and tie members disposed transversely around the wrapper and the group of plates 100 therewithin.

In testimony whereof I have signed my name to this specification in the presence of the two subscribing witnesses.

HOWARD EARL SIMMONS.
